Application July 19, 1933, Serial No. 681,093

23 Claims. (Cl. 181—42)

This invention relates to silencers of the type used in connection with intakes and exhausts of gas engines and air compressor intakes, on blowers, and for noise producing moving gases from other sources.

This invention is an improvement on the so-called resonator type of silencer in which one or more tuned resonators are used to attenuate sounds passing through a duct. It is an object of this invention to provide a novel form of sound attenuating resonator in which the three components of the acoustic impedance thereof are structurally substantially separate so that each component may be changed independently of the others whereby for any given volume of resonance chamber the resonance frequency may be changed over a wide frequency band without affecting materially the decrement (sharpness of tuning) and, also, the decrement may be varied substantially independently of the resonance frequency to produce the desired characteristics. It is a further object to provide a resonator of such construction that a single chamber efficiently attenuates a broad band of frequencies. The acoustical terms used herein are those approved by the Acoustical Society of America.

In the accompanying drawings, various forms of this invention are illustrated in diagrammatic form. This invention, however, is not limited to these specific forms.

Fig. 1 is a sectional view of a simple type of silencer utilizing this invention;

Fig. 7 is a similar view of a silencer containing two resonance chambers of my invention in parallel;

Fig. 8 is a similar view of another form of silencer incorporating my invention;

Figs. 9 and 9a are cross sectional views of a

different type of the silencer of my invention containing two resonance chambers;

Fig. 10 is a cross-sectional end view of another type of the silencer of my invention containing two resonance chambers;

Fig. 11 is a cross sectional end view of a silencer which is not circular in cross section incorporating my invention;

Figs. 12 and 13 are sectional views of modified forms of silencers incorporating my invention in which a central resonance chamber is incorporated;

Fig. 14 is a sectional view of one form of exhaust silencer incorporating this invention;

Fig. 15 is a similar view of another type of resonator construction in which the principles of this invention are incorporated; and

Fig. 16 is a similar view of another modification;

Fig. 17 is a cross sectional view along the radial entrance of a square silencer having an offset duct;

Fig. 18 is a similar view of a hexagonal silencer; and

Figs. 19 and 20 are similar views of silencers incorporating various other structural modifications.

In the silencer of Fig. 1 the sound travels along duct 11. In intake silencers the sound moves in a direction opposite to the flow of air, whereas in exhaust silencers the gases and sounds move in the same direction. The resonance chamber 12 is an annular chamber which is closed except for openings 13 whereby it is coupled to the annular radial passage 14 formed by spacing an annular disk 15 interiorly of and adjacent one of the end flanges 16 and 17. Openings 13 and annular radial passage 14 constitute the neck of the resonator. Radial passage 14 preferably is substantially of the same width throughout its length and opens into the duct 11, preferably without any restriction at this entrance. Any restriction or restrictions in the radial passage add to the resistance. In this construction (within limits) the resonance chamber 12 forms substantially the entire compliance (capacitance) of the resonator, the openings 13 form substantially the entire resistance and the radial passage 14 forms substantially the entire inductance (inductance) of the resonator, that is, the construction is such that the three components of the acoustic impedance of the resonator are structurally substantially separate. For example, the resistance of radial passage 14 is

5

20

30

35

40

45

50

55

substantially negligible as compared to the resistance of openings 13. In extreme cases there is more overlapping, as, for example, when the radial passage 14 is very narrow and the resistance thereof becomes comparatively large.

In the constructions of this invention in which the three components of the impedance of the resonator are structurally separate, the designing of a resonator for attenuating undesired frequencies is greatly simplified. Furthermore it is possible structurally to locate the three components so that each component and the entire combination may function at high efficiency. The radial type neck offers a minimum of resistance to the oscillatory movement of the sound waves entering it. The improved results obtained are evidenced by the excellent attenuation it is possible to obtain with a single chamber in any single silencer over a broad band of frequencies and especially broad bands of low frequencies when a compliance chamber of small volume must be used.

In a specific intake silencer for an automobile the duct 11 was $1\frac{1}{4}$ inches in diameter, the resonance chamber had an outside diameter of $7\frac{1}{2}$ inches and was 3 inches long. The radial passage was $\frac{1}{8}$ inch wide and there were about 45 holes $\frac{1}{4}$ inch in diameter spaced on about $\frac{1}{2}$ inch centers at about $\frac{1}{2}$ inch from the outer periphery of disk 15. This silencer attenuated satisfactorily a continuous band of frequencies of from 175 cycles to about 400 cycles, though peaking at 200 cycles. These data are illustrative of the wide band of frequencies, and especially low frequencies, which may be attenuated satisfactorily by a small single resonance chamber with a neck made in accordance with the principles of this invention. It is especially desirable that automobile intake silencers attenuate a wide band of frequencies because of the wide range of engine speeds used in the operation of automobiles.

The construction has several advantages over the structures of the prior art. It is possible to vary the resonance frequency of the resonator over a considerable range by changing the length and/or width of the radial passage 14 (within limits) without affecting the decrement substantially. However, if the width of the radial passage is decreased greatly as for example, to less than $\frac{1}{4}$ inch in the above specific intake silencer, the resistance thereof increases rapidly and is no longer negligible compared to the resistance of the openings 13. Such narrow widths are seldom used because the attenuation is decreased greatly by the high resistance. Decreasing the width or increasing the length of the passage lowers the resonance frequency. Fig. 1 shows a construction wherein the width of the inertance passage may be varied so that the silencer may be readily tuned to any frequency. End flange 16 is provided with an inwardly extending interiorly threaded shoulder 9 adapted to engage screw threads upon the exterior of the shoulder 8, as shown. By adjusting the position of the end flange toward and away from the annular disc 15, the width of inertance passage 14 may be varied. The spaced openings 13 preferably are placed at points farthest removed from the duct 11 so that advantage may be taken of the full length of the neck or radial passage 14. These openings need not be placed immediately adjacent the outer edge of the disk 15 so far as the effect of the inertance on the resonance frequency is concerned. However, if they are placed

too far from the outer edge the inertance of the passage is affected.

The decrement of the resonator is dependent upon the aggregate area of openings 13 and this area may be regulated to obtain the desired results. If the total area is large, the resistance is low and the decrement is small, that is the "tuning" is sharp, the attenuation at the peak frequency being more pronounced. As the area of opening is decreased the sharpness of tuning 10 and the peak attenuation decreases, while the attenuation at the adjacent frequencies increases. The tuning thereby is broadened so that a wide band of frequencies is attenuated efficiently. If the total area of opening is decreased too much 15 the attenuation also is decreased and the silencing is impaired. It is desirable to have the holes spaced closely enough to each other so that no portion of the pressure waves will be blocked, which would decrease the attenuation. A circular narrow slot may be used but the spaced holes are preferred for commercial production. If the disk 15 is a thin sheet, the holes have practically no inertance or compliance in comparison with the balance of the resonator. By 20 changing the size and/or number of holes it becomes possible (within limits) to change the resistance or decrement without appreciably affecting the resonance frequency. This may be accomplished in the silencer shown in Fig. 1 by 25 removing the flange 16. The holes 13 may then be increased in diameter or number. In practice it is desirable to start with a small number of holes or holes of a small diameter and increase the size and/or number until the desired decrement is obtained. However, excess holes may be closed by lead, putty or other like suitable material. This type of construction provides a concentrated resistance between the inertance and compliance instead of a resistance distributed 30 throughout the neck as in attenuating resonators of the prior art. Although the concentrated resistance may be placed at any point in the neck the most desirable place is between the main compliance and the main inertance. If shoulders 35 are formed at the edge of openings 13 the inertance of these openings is increased and therefore such shoulders or flanges should be omitted or made small if the inertance of the neck of the resonator is to be independent of the 40 area of the resistance openings.

In the practical application of this invention the advantages are apparent in the following examples. In a resonator whose resonance frequency is too high and which has a resonance chamber 55 of a given volume which can not be enlarged because of space limitations, it is possible to decrease the resonance frequency without appreciably disturbing the decrement or appreciably affecting the attenuation by merely 60 increasing the length of the radial passage if the width can not be decreased because of decreased attenuation which would result. The dimensional changes occasioned thereby are small as compared to the change in the compliance volume which would be necessary for the same frequency change. The length may be increased by the construction shown for radial passage 21, 22 in Fig. 3. The decrement is not disturbed appreciably because the change in length of the radial 65 passage does not affect appreciably the total resistance of the resonator. Any slight decrement change which may result may be corrected by changing the area of openings 13 slightly. In the constructions of the prior art an increase in length 70

of the neck of the resonator not only affects the inertance but it also affects the resistance substantially and thereby changes the decrement. On the other hand, in the constructions of this invention, if the volume of the resonance chamber can not be changed and it is necessary to change the decrement this may be effected without affecting the resonance frequency by merely changing the total area of the openings 13. The advantages of this construction are apparent to those skilled in the art.

In Fig. 3 the sound duct 18 is surrounded in part at least by an annular resonance chamber 19. The entrance passage to this chamber consists of radial passages 21 and 22 connected with each other in series by annular opening 23, and concentrated resistance openings 24 in annular disk 25. Annular opening 23 should be of an area which will not cause any appreciable increase in the resistance of the radial passages 21 and 22. Although this combination of the two radial passages is not as effective as a single radial passage whose length is equal to the combined length of the two radial passages, nevertheless this construction is more compact and may be used where space requirements prohibit the use of a long single radial passage. At the opposite end a high frequency silencing chamber 26 of the conventional type may be used. This is formed by blocking off one end of the annular chamber by annular disk 27 and opening the chamber 26 so formed into duct 18, the opening usually not being restricted as in the resonator used at the opposite end.

Fig. 5 illustrates a compound resonator. In addition sound absorbing material is used to silence high frequencies in the sound passing through the duct 28. As in Fig. 1 the resonance chamber 29 is connected with the duct by means of the radial passage 30 and the concentrated resistance openings 31. A second resonance chamber 32 is formed adjacent the resonance chamber 29 by means of annular disk 33, the two chambers being connected by suitable openings 34. Such a compound construction may be used for special purposes. The sound duct 28 is also lined by sound absorbing material 35 faced by perforated metal 36 or other foraminous material or other retaining material. The perforated or other foraminous facing may be omitted when certain types of molded absorbing materials are used.

In Fig. 6 duct 37 is immediately surrounded by small annular chamber 38 for the removal of high frequencies, this chamber in turn being surrounded by the compounded resonance chambers 39 and 40. The neck of chamber 39 is formed by radial passage 41 opening into duct 37 and concentrated resistance openings 42. Connection between chambers 39 and 40 is made by means of radial passage 43 and concentrated resistance openings 44.

In Fig. 7 the duct 45 is surrounded by two annular resonance chambers 46 and 47. The inner chamber 46 connects with duct 45 by means of radial passage 48 and concentrated resistance openings 49. The outer resonance chamber 47 connects with duct 45 through radial passage 50 and concentrated resistance openings 51.

In Fig. 8 the silencer consists of a short cylinder of large diameter. In this construction the sound duct 52 is connected with the resonance chamber 53 by a separately inserted radial passage or slot 54 and concentrated resistance openings 55. The openings may also be in the periphery 56.

Figs. 9 and 9a are cross-sections of a modification of the silencer through the radial passage 14 of Fig. 1. The duct 57 is surrounded by two segmental resonance chambers 58 and 59 formed by segmental partitions 60 and 61 inserted in the resonance chamber. These segmental partitions extend through the radial passage and form two segmental radial passages. These segmental radial passages open into duct 57 and are connected with the segmental chambers by concentrated resistance openings 62.

Fig. 10 is a cross sectional view through the radial passage of a silencer somewhat similar to that of Fig. 7 and having two annular resonance chambers 63 and 64 which surround the duct 65. The resonance chambers are reached through a common radial passage and are separated from each other by an annular partition 66 which does not extend into this passage. Concentrated resistance openings 67 and 68 are formed between the common radial passage and chambers 63 and 64 respectively. If chamber 64 is of relatively small volume it attenuates a range of frequencies above the range attenuated by chamber 63.

In Fig. 11 is shown the cross sectional end through the radial passage of a silencer in which the cross section is not round. This oval form may be applied to any of the types previously described. The duct 69 is surrounded by the resonance chamber 70 reached by a radial passage as in Fig. 1 and concentrated resistance openings 71. The contour of the silencer, however, may be any desired shape such as square, hexagonal, etc., and the duct may be off-center as illustrated in Figs. 17 and 18.

In Fig. 12 the sound duct 72 surrounds the resonance chamber 73. A disk 74 is spaced from the end wall 75 of the chamber and forms a radial passage 76. This passage communicates with the interior of the chamber 73 by means of concentrated resistance openings 77. One opening may be used instead of the several shown. The front of disk 74 may be faced with sound absorbing material 74a. An air cleaning material 78 may be inserted in duct 72 if the silencer is to be used for an automobile engine intake.

In Fig. 13 the construction is similar to Fig. 12 except that the radial passage 79 between the duct 79a and concentrated resistance openings 80 in the end wall 81 of the resonance chamber 82 is formed in another way. The radial passage 79 formed by spacing disk 83 away from end wall 81 is closed at its periphery. Entrance is made from duct 79a by central opening 84.

Fig. 14 shows this invention applied to one type of exhaust silencer. Because of the intensity of the pressure waves which have to be silenced it is desirable to use a series of chambers 85, 86 and 87 which are connected to the main duct 88 by means of radial passages 89, 90 and 91 and concentrated resistance openings 92, 93 and 94, respectively. Because of the hard service to which exhaust mufflers are subject it is not desirable to have any portion of the duct 88 "floating". In Fig. 14 this duct is shown as made in one piece. Large openings 95, 96 and 97 in duct 88 provide the connections with radial passages 89, 90 and 91, respectively. The resistance at these entrances is thereby kept at a minimum and the structure is of sufficient strength for exhaust muffler purposes.

Although Figs. 1 to 14 show the principle of concentrated impedance components applied specifically to resonators in which a radial entrance is used this principle may be applied to resonators

of the prior art. For example, Figs. 15 and 16 show a silencer in which the neck of the resonator is of the annular type entrance of the prior art, and the concentrated resistance between the inertance and compliance is shown at two different points. In Fig. 15 duct 98 is surrounded by inner and outer annular shells 99 and 100, respectively. The compliance chamber 101 is acoustically connected with duct 98 by means of the annular inertance passage 102 between the wall of duct 98 and shell 99, the opening 103 in the duct wall and concentrated resistance openings 104 in the end flange 105 between the shell 99 and the wall of duct 98.

15. In the construction shown in Fig. 16 the duct 98 is surrounded by inner and outer annular shells 106 and 107, respectively. The compliance chamber 108 is acoustically connected with duct 98 by means of the annular inertance passage 109 between the wall of duct 98 and shell 106, the opening 110 in the duct wall and concentrated resistance openings 111 in annular shell 106 at the end removed from opening 110. Flange 112 closes the end of the annular passage. The two constructions of Figs. 15 and 16 may be combined, that is, concentrated resistance openings may be used in both the inner annular shell and the end flange in the same resonator.

If the principle of concentrated impedance components is applied to the resonators of the prior art as in Fig. 15 it is desirable to design the structure supplying the inertance component so that it has a small or substantially negligible resistance as compared to the concentrated resistance, so that the maximum benefit may be obtained.

In Figs. 1 to 14 the radial necks are shown to be of constant width. Under certain conditions it may be desirable to change the width of the radial passage along its length. For example, in Fig. 19, the disk 15 is replaced by a disk 113 in the form of a flat truncated cone to thereby provide a radial passage 114 which varies in width throughout its length. Resistance openings 115 lead from the radial passage to the compliance chamber 116 enclosed in shell 117. The radial passage opens into duct 118 in which occur the undesirable sounds which are attenuated. In Fig. 20 is shown the same modification applied to the annular neck of Figs. 15 and 16. The annular neck of these modifications is changed in Fig. 20 to the shape of truncated cone 119 containing resistance openings 120 which lead into compliance chamber 121 within shell 122. The neck opens into duct 123 in which occur the sounds to be silenced. Other variations will be apparent to those skilled in the art.

Sound frequencies which are attenuated vary in some inverse function of the volume of the resonance chambers. While the resonators illustrated herein incorporating the herein described invention are mostly of the low frequency absorbing type the same principle is used in resonators that attenuate high frequencies. For example in Fig. 19 the conventional high frequency absorbing chamber 26 of Fig. 3 is replaced by a chamber 124 of about equal size with a radial entrance 125 and concentrated resistance openings 126. This construction may be used to attenuate a narrow or wide band of high frequencies depending upon the total area of the resistance openings. The high frequency attenuating chamber 38 of Fig. 6 may be modified similarly as shown in Fig. 19 so that the neck 127 of the resonance chamber 128

is radial with high resistance openings 128 between the chamber and the radial neck.

It may also be advantageous under certain conditions to introduce a sound attenuating material such as felt, mineral wool, metallic wool, pumice granules and the like in the resonance chambers. This material may be especially helpful in the small high frequency attenuating chambers. Such a construction is shown in Fig. 19 in which high frequency attenuating chamber 130 having 10 radial neck 131 and resistance openings 132 is filled with cotton linters 133.

I claim:

1. In combination with a duct, a silencer comprising a shell having flanges attached thereto 15 surrounding at least a portion of said duct and enclosing an annular chamber, an annular disk spaced a uniform distance from and adjacent interiorly of one of said flanges and forming an end wall of said chamber, the space between said 20 flange and said disk opening into said duct, said annular disk having one or more acoustic-resistance openings therein.

2. In combination with a duct, a silencer comprising an annular chamber divided into two or 25 more segmental parts surrounding at least a portion of said duct, segmental radial acoustic inertance passages registering end-wise with the segmental portions of said chamber and of substantially negligible acoustic resistance opening 30 into said duct, and an acoustical resistance opening or openings between the corresponding segmental radial passages and segmental chambers.

3. In combination with a duct, a silencer comprising a resonator which comprises a chamber 35 associated with said duct, an inertance passage opening into said duct and being of such shape and dimensions as to provide substantially all of the inertance of said resonator and having substantially negligible acoustic resistance, and a 40 concentrated acoustic resistance of substantially negligible inertance comprising one or more openings between said chamber and said inertance passage to thereby form a construction in which said passage and said openings each 45 respectively provide substantially all the inertance and resistance of the neck of said resonator.

4. In a silencer in which objectionable sounds are attenuated by means of a tuned resonator, the combination of a resonance chamber with an 50 acoustic inertance passage and acoustic resistance means therebetween, the shape and dimensions of said inertance passage being such that the acoustic resistance thereof is sufficiently small in proportion to the total acoustic resistance of the 55 resonator so that the total acoustic resistance of said resonator is substantially independent of the length of said passage.

5. The structure of claim 4 in which the resonance chamber is connected with the inertance 60 passage by one or more acoustic resistance openings of substantially negligible acoustic inertance.

6. In combination with a duct, a silencer comprising a resonator having a neck for attachment to said duct, said neck providing separate concentrated resistance means and inertance means for said resonator, one or more openings in said neck providing said concentrated acoustic resistance means of substantially negligible inertance and being of such shape and so located in the 70 neck of said resonator that it is variable independently of the principal inertance means in the neck of said resonator, the shape and dimensions of said neck being such that the portion thereof not including said resistance means provides sub- 75

stantially all of the inertance of said resonator and has a resistance sufficiently small in proportion to the total resistance of said resonator that the total acoustic resistance of said resonator is substantially independent of the length of the inertance passage.

7. In a silencer adapted to be attached to a duct in which the sounds to be attenuated are borne, a resonator therein for attenuating sounds by means of acoustic impedance, said resonator being a structural combination comprising a chamber and an annular passage with a wall therebetween and connected by one or more openings, said annular passage being concentric with said duct, said chamber, passage and openings therebetween each respectively providing substantially all of the compliance, inertance and resistance forming said acoustic impedance.

8. In a silencer adapted to be attached to a duct in which the sounds to be attenuated are borne, a resonator therein for attenuating sounds by means of acoustic impedance, said resonator having a neck comprising the structural combination of an annular passage with openings in a wall thereof, said annular passage being concentric with the duct in which said sounds are borne, said passage and said communicating openings each respectively providing substantially all of the inertance and resistance of said neck.

9. In combination with a duct, a silencer comprising a resonator, said resonator comprising an acoustic compliance chamber, an annular acoustic inertance passage of substantially negligible acoustic resistance concentric with said duct, said passage connecting with said duct substantially throughout its intersection therewith, and one or more acoustic resistance openings between said annular passage and said chamber, said opening or openings having substantially negligible acoustic inertance.

10. The structure of claim 9 in which the acoustic inertance passage extends at substantially a right angle from the duct.

11. In combination with a duct, a silencer comprising a resonator, said resonator comprising an annular chamber surrounding at least a portion of said duct, an annular acoustic inertance passage of substantially negligible acoustic resistance concentric with said duct and surrounding at least a portion thereof, said passage connecting with said duct substantially throughout its intersection therewith, and one or more acoustic resistance openings between said passage and said chamber.

12. The structure of claim 11 in which the acoustic resistance openings are a series of spaced small holes.

13. In combination with a duct, a silencer comprising a resonator, said resonator comprising a chamber adjacent said duct, an acoustic inertance passage of substantially constant width extending radially from a perimeter of said duct and communicating with and extending from said duct substantially throughout the length of said perimeter, and one or more acoustic resistance openings between said radial inertance passage and said chamber.

14. In a silencer, a resonator comprising a side branch resonance chamber associated with a duct, an acoustic inertance passage communicating with and extending from said duct substantially throughout the length of the perimeter of said duct, and acoustic resistance means comprising one or more openings between said passage and said chamber.

15. In combination with a duct, a silencer comprising a resonator, said resonator comprising an acoustic compliance chamber, two adjacent annular disks spaced apart and mounted on said duct, the space between said disks opening into said duct substantially throughout a perimeter thereof, and one or more acoustic resistance openings between said compliance chamber and said space between said disks.

16. In combination with a through duct in which sounds to be attenuated are borne, a silencer comprising one of the chambers formed by a plurality of telescoped cylinders whereby an annular chamber is formed around a central cylindrical chamber, the other of said chambers forming said through duct, said first chamber forming a compliance chamber, an annular acoustic inertance passage of substantially negligible acoustic resistance opening into and being concentric with said duct, and one or more acoustic resistance openings between said compliance chamber and said annular acoustic inertance passage.

17. The silencer of claim 16 wherein the acoustic resistance openings are a series of spaced small holes.

18. The silencer of claim 16 wherein the acoustic resistance openings are a series of spaced small holes opening into that portion of the annular passage farthest removed from said duct, the total area of the openings being small whereby the tuning of the silencer is not sharp.

19. The method for tuning a resonator by means of acoustic inertance without substantially affecting the decrement thereof which comprises connecting the resonance chamber of said resonator with the duct containing the sounds to be attenuated by means of a concentrated resistance element and a passage of substantially negligible resistance and varying a dimension of said passage.

20. The method for varying the decrement of a resonator without substantially affecting the resonance frequency thereof, which comprises connecting the resonance chamber of said resonator with the sound duct by means of a passage of negligible resistance, and one or more openings comprising concentrated resistance between said chamber and said passage, said opening or openings having substantially negligible acoustic inertance, and varying the concentrated acoustic resistance by changing the area of the opening or openings between said resonance chamber and said passage.

21. The construction of claim 14 in which a second resonance chamber is connected to said first resonance chamber by means of the combination of an acoustic inertance passage of substantially no acoustic resistance, and acoustic-resistance means comprising one or more openings between said second resonance chamber and said second inertance passage.

22. The structure of claim 3 in which said chamber contains a sound absorbing material.

23. In combination with a duct, a silencer comprising a substantially closed shell surrounding at least a portion of said duct and enclosing a chamber, two adjacent, spaced-apart annular disks extending outwardly from said duct and within said chamber, the space between said disks opening into said duct, and one or more acoustic-resistance openings between said chamber and said passage between said disks.
